UNITED STATES PATENT OFFICE.

ANDREW HAUG, OF SAN FRANCISCO, CALIFORNIA, ASSIGNOR TO ALVIN R. CLARY, OF SAN FRANCISCO, CALIFORNIA.

SEPARABLE FASTENER.

SPECIFICATION forming part of Letters Patent No. 710,863, dated October 7, 1902.

Application filed May 11, 1901. Serial No. 59,863. (No model.)

To all whom it may concern:

Be it known that I, ANDREW HAUG, a citizen of the United States, residing at 116 Second street, in the city and county of San Francisco, State of California, have invented certain new and useful Improvements in Separable Fasteners; and I do hereby declare the following to be a full, clear, and exact description of said invention, such as will enable others skilled in the art to which it most nearly appertains to make, use, and practice the same.

This invention relates to fasteners, and particularly to separable garment - fasteners. One type of fastener in this class which has come into general use consists of a stud with a compressible head adapted to be forced into an aperture of slightly less diameter which engages the neck of the stud, holding the parts together against the expansion of the head. This type at best is only a frictional lock, the repeated locking and separating of which very soon kills the expansibility of the head, rendering the fastener uncertain in its action.

The object of this invention is to provide a fastener positive in action and which cannot be opened except intentionally.

The invention consists of a plate adapted to be attached to one edge of the material to be joined, a stud with an annular groove attached to said plate, a plate adapted to be attached to the opposite edge of the material to be joined, an upset portion upon said second plate with an opening to admit the stud upon the first plate and having a mouth in its side, and a flat spring attached at one end to the second plate, the free end extending through the mouth aforesaid and under said upset portion and having an opening normally out of coincidence with said opening in the upset portion, so that the edge of the opening in the spring will engage the annular groove in the stud, forming a positive engagement of the separable parts of the fastener.

In the drawings, Figure 1 is a plan view of the separable parts of a fastener constructed in accordance with this invention, the parts being disengaged. Fig. 2 is a side elevation of the same. Fig. 3 is an enlarged detail side elevation, in longitudinal cross-section, showing the separable parts in locked engagement.

In the description of the construction with reference to the drawings the stud will be designated by the letter A, the attaching-plate therefor by A', the plate for the locking mechanisms by B, and the spring by C. The stud A is formed integrally with or may be riveted to the plate A' and is provided with the annular groove A². The perforations A³ are provided in the plate A' to attach the same to the fabric. The upset B' is struck up from the metal of the plate B and is provided with the opening B² in its top and mouth B⁶ in its side. The spring C is attached to the plate B by means of a bur B³, struck up therefrom, extending through a hole in the end of the spring and riveted. The perforations B⁴ provide a means for attaching the plate B to the fabric. To stiffen the plate B, the bead B⁵ is upset under the spring C. The spring C consists of a narrow strip bowed upward between the rivet B³ and upset portion B' and having the extension C', with opening C², extending through mouth B⁶ and under portion B'.

The operation is as follows, presuming the separable parts to be upon opposite sides of a placket or the like, the stud A being upon the side that laps over: The edges are drawn together, the stud A forced through opening B² and locked in position by the edge of the opening C² in the spring engaging the annular groove A². To separate the parts, it is necessary to compress the bow in the spring, which throws the opening C² forward into coincidence with B², releasing the stud.

For an illustration of the preferred mode of attaching the fastener to the fabric see dotted construction, Fig. 3. This leaves stud A and portion B' the only parts exposed, and this only when parts are separated. It is obvious that the various uses of this fastener will call for slight changes in mode of attachment or even in construction of the fastener.

Having thus described this invention, what is claimed is—

In a separable fastener, the combination with a plate having an upset or raised portion provided with a mouth at one side and an opening or slot in its top, of a bowed or leaf spring having one portion anchored to the plate and free end which extends through the mouth and under the raised or upset

portion aforesaid and there provided with an opening or slot normally out of register with the opening in the raised portion but adapted to be brought into register there-
5 with when the spring is compressed, an at-
taching-plate, and a headed stud on said plate
which is adapted for entry through the aper-
ture in the raised or upset portion and for

reception in the opening of the spring and en-
gagement by the latter.

In testimony whereof I have hereunto set
my hand this 29th day of April, 1901.

ANDREW HAUG.
